UNITED STATES PATENT OFFICE.

JOHN H. BARR, OF ITHACA, NEW YORK, ASSIGNOR TO BARR-MORSE CORPORATION, A CORPORATION OF NEW YORK.

LINE LOCK AND MARGIN RELEASE.

Application filed January 8, 1926. Serial No. 79,913.

This invention relates to typewriting mechanism and particularly to line lock and margin release features thereof.

An object of the invention is to provide 5 an improved typewriting mechanism by which operation of the printing mechanism will be obstructed when the carriage reaches a selected point in its travel, such as at the desired end of a line being typed, and by 10 which the obstruction to the keys may be removed by a simple manual operation of the typist when necessary in order to complete a syllable or word; and with which the point in the travel at which operation of the printing mechanism is obstructed may be varied 15 at will.

A further object is to generally improve and simplify such improved mechanism for accomplishing these purposes, and obtain a 20 construction which will be more compact, dependable, durable, convenient, and relatively inexpensive.

A further object is to provide an improved mechanism for accomplishing each and all 25 of the above objects which may be largely formed of stamped flat sheet metal and wire rods.

A further object is to provide an improved stop element, cam element, or margin stop, 30 which may be largely formed of stamped sheet metal and assembled in a simple manner, and be relatively durable and inexpensive.

Various other objects and advantages will 35 be apparent from the following description of one embodiment of the invention, and the novel features will be particularly pointed out hereinafter in connection with the appended claims.

40 In the accompanying drawings:—

Fig. 1 is a diagrammatic elevation of a portion of a typewriting machine constructed in accordance with this invention;

Fig. 2 is a rear elevation of a segment and 45 universal bar which are utilized as a part of the invention;

Fig. 3 is a plan of part of the bottom portion of the typewriter frame, and illustrating part of the mechanism constituting the 50 invention;

Fig. 4 is an elevation of the margin release key and the manner of its support; and

Fig. 5 is a rear elevation of a portion of the stop bar and one of the improved cam or 55 stop elements thereon.

In the illustrated embodiment of the invention, the carriage 1 (see Fig. 1) is supported in any suitable or desired manner for travel across the frame 2 of the machine. Such support for the carriage may comprise 60 a guide bar or track 3, having ball raceways 4 along its two edges for receiving and guiding ball bearings 5 which are interposed between the raceways and guide flanges 6 of the carriage. The machine is also provided 65 with any suitable printing mechanism 7, such as type bars pivoted to the segment 8 and operating upon a universal bar 9.

One form of such universal bar is shown 70 in Figs. 1 and 2 and includes an arcuate bar disposed in a groove 10 in the rear face of the segment 8, so as to be engaged and cammed rearwardly by the heels of the type bars as the type bars move toward printing position. The arcuate bar is supported by 75 angularly positioned levers 11 which are pivoted at 12 and 13 to supporting ears 14 and 15 of the segment. The levers 11 are pivotally connected at one end to spaced points 80 of the arcuate bar in the groove 10, and are interconnected at their other ends in pairs by a rocking joint. For example, a pin 16 carried by one of each pair of levers 11 85摇滚ly engages in an aperture in the adjacent end of the other lever of the same pair.

By this mechanical interconnection of different points along the length of the arcuate bar section of the universal bar, all points of the arcuate bar will always partake of equal movements, regardless of which type bar of 90 the segment happens to be operating thereon. This universal bar construction forms the subject matter of another application and, inasmuch as, per se, it forms no part of the present invention, further details herein will 95 be omitted.

To this universal bar 9, a link 17 is connected, such as by a pivot pin 18, the link 100 extending rearwardly of the segment and having at its free end a slot 19 elongated in a direction lengthwise thereof. A screw, pin or bolt 20 is provided upon a bracket 21 of the frame 2 to slidably support the free end of the link 17. To accomplish this purpose, the shank of the pin or bolt 20 passes through the slot 19 and slidably confines the link 17 to the bracket 21. Thus the link 17 will have a movement of substantial translation in a direction endwise of itself, whenever the universal bar 9 is operated by the 105 110

heel of one of the type bars of the printing mechanism.

A locking pawl 22 is pivoted at 23 to a bracket 24 of the frame 2, so as to be movable into a position at the end of the link 17 as shown in dash lines in Fig. 1. When the pawl is in the dash position shown in Fig. 1, it will lie closely adjacent the end of the link 17 and prevent endwise movement thereof, and the latter, through its connection to the universal bar, will prevent or obstruct operation of the type bars of the printing mechanism. When the pawl 22 is in its lower position as shown in full lines in Fig. 1, it will clear the link 17 and permit of a free operation of the latter.

A lever 25 is pivoted to the bottom of the frame 2 in any suitable manner, such as by bearing clips 26 (see particularly Fig. 3) which fit over the lever and rotatably confine it to the frame. The lever is preferably provided with an intermediate offset or transverse portion which connects the two arms of the lever, and the clips 26 are disposed over the transverse section adjacent the ends thereof, so as to not only confine the lever to the frame but also prevent its lateral displacement.

One arm 27 of the lever 25 extends into proximity to the pawl 22 and has an angular end 28 which passes through a slot 22^a in the pawl, so that when the lever is rocked it will cause a rocking of the pawl 22 into and out of a position in which it obstructs operation of the printing mechanism. The other arm 29 of the lever 25 extends into proximity to the carriage for operation by parts carried thereon, as will be explained shortly.

The arms 27 and 29 of the lever are in different planes, that is, each arm and the transverse section of the lever are in a plane which is oblique or inclined to the plane of the other arm of the lever and the offset or transverse bearing portion thereof, so that the lever may have a limited rocking motion upon the bottom plate of the frame against which it is confined by the bearing clips 26. A spring 25^a may act upon the arm 27 to urge it downwardly and yieldingly hold arm 29 in its upper position.

A margin or stop rack bar 30 is suspended by arms 31, connected to its ends, from the carriage 1, the arms 31 having eyes or loops 32 which are supported upon a shaft or pins 33 of the carriage. The arms 31 and rack bar 30 together are in the shape of a bail which is dependently hung from the carriage so as to move endwise of itself with the carriage, and at the same time be free to swing forwardly and rearwardly of the machine, that is, in a direction laterally of its travel with the carriage for a purpose which will hereinafter appear.

A clip 34 of sheet metal is slidably mounted upon the rack bar 30, and may comprise a

body of sheet metal which is fitted against one face of the rack bar, with its edges 35 turned over the edges of the rack bar and for a short distance across, but slightly spaced from, the other face of the rack bar. The clip is provided with notches 36 in its upper and lower edges, which, in effect, are apertures in the edges 35.

A latch piece 37 has an arm 38 (see Figs. 1 and 3) extending through the two apertures 36 of the clip and along the face of the rack bar 30 over which the edges 35 are turned, but between said edges and that face of the rack bar, so as to be confined against the rack bar and yet be free to move transversely of the rack bar across a face thereof. The upper end of the latch piece 37 extends over the upper edge of the rack bar, then over and down in front of the other face of the rack bar but in spaced relation thereto, and at its other end terminates in a reduced pin section 39.

The lower end of the arm 38 of the latch piece, which is confined between the edges 35 and one face of the rack bar 30, has lateral flanges 40 which are turned or bent transversely to the rack bar so as to cross the lower edge of the rack bar in which rack teeth or notches 41 are provided. Thus, as the latch piece moves vertically, that is, across a face of and transversely of the rack bar, the flanges 40 which underlie the rack bar will move into or out of the notches 41 in the edge of the rack bar. When the flanges 40 are in the notches 41 the latch piece will lock the clip against sliding movement along the rack bar, and when the latch piece is depressed the flanges 40 will be carried out of the notches in the rack bar and release the clip for sliding movement along the rack bar to new adjusted positions.

A cam lever 42 is provided with a lateral or angular branch 43 which is pivoted by rivet 44 to the clip 34, so that the body of the lever will depend somewhat below the clip. The free end of the lever is provided with an upstanding or lateral branch 45, the extreme free end 46 of which is flanged toward and abuts the adjacent face of the rack bar. One end of the clip is provided with a notch or slot 47 in which the angular end or flange 46 of the lever 42 is received, which limits the oscillating or rocking movements of the lever 42.

The cam lever 42 intermediate of its ends is also provided with a flange or ear 48 having an aperture 49 therein, through which the reduced end 39 of the latch piece extends. The aperture 49 is somewhat larger than the reduced end 39 of the latch piece which extends therein, so that the cam lever may rock to the extent permitted by the limits of the slot 47 without binding upon the end 39 of the latch piece. A helical compression spring 50 surrounds the reduced

end 39 of the latch piece and is confined under compression between a shoulder of the latch piece and the flange 48 of the lever 42, so as to have the double function of yielding holding the cam lever in its lowermost position, shown in full lines in Fig. 5; and also urging the latch piece in an upward direction to carry the flanges 40 thereof into the notches 41 of the rack bar.

10 The lever 42 depends sufficiently to engage and rock the lever arm 29 of the lever 25, when the carriage has reached a selected position depending upon the position of the clip upon the rack bar. The lever 42 is provided, upon its forward edge which engages the lever arm 29, with a cam surface 51 which serves as a nose to cam the lever arm 29 downwardly while the carriage moves by increments under the control of the escapement as permitted by the printing mechanism.

The other end of the lever 42, which is further from the pivot 44, may be oblique as at 52. The cam lever 42 may also have 25 a pin 53 projecting from a face thereof for operating an audible signal device in any suitable manner which, per se, forms no part of the present invention and which, for that reason, is not illustrated.

30 A crank rod 54 (see Fig. 3) is pivotally mounted in brackets 55 and 56 carried by the bottom part of the frame. The rod 54 extends substantially parallel to the rack bar 30 and in proximity thereto. One end of 35 the crank rod 54, adjacent the portion which is rotatably mounted in the bracket 55, is turned angularly as at 50 to form a crank arm or cam arm of such a length as to engage with the rack bar 30 and swing it rearwardly when the crank rod 54 is oscillated in the brackets 55 and 56 in one direction.

A spring 57 is connected to the arm 56 and to a suitable anchorage pin 58 of the frame, 45 so as to normally hold the arm 56 in retracted position away from the rack bar 30. The arm 56 may be placed at approximately the center of the machine, so that throughout all of the travel of the carriage, it will 50 always be in proximity to and capable of engaging the rack bar 30 when oscillated for that purpose. The other end of the crank rod 54 is turned angularly as at 59 to form a second crank arm, and the extreme end 55 of this arm is turned angularly as at 60 to form a crank pin.

A push rod 61 is slightly mounted at one end in an aperture 62 of a comb 63 of the frame, and at an intermediate point is loosely 60 and slidably mounted and guided in an aperture 64 in a rib 65 of the frame. The other end portion 66 of the push rod 61 drops downwardly into proximity to the bottom of the frame, then toward the rack bar 30, terminating just forwardly of the latter in

an upstanding arm 67 which turns over and rearwardly to form a loop 68 as the terminal for the push rod, which pivotally receives the crank pin 60 of the crank arm 59.

A key stem 70 of a margin release key 71 is connected to one side of a collar 72 which is fixed upon the rod 61 at a point adjacent the comb 63, and this stem 70 also is provided with a pin 73 which is slidably mounted in the comb 63. Thus when the key 71 (Fig. 4) is pushed rearwardly, it will shift the rod 61 rearwardly until arm 67 is in the dash line position (Fig. 1), and by reason of its pivoted connection to the crank pin 60, will rock the crank rod 54 through an angular extent which will carry the crank arm 56 into engagement with the rack bar 30, as shown in dash lines in Fig. 1, and swing it rearwardly until the cam lever 42 clears the lever arm 29. The extra pin 73 prevents rotation of the rod 61 about its own axis which might tend to disengage its looped end 68 from the crank pin 60 or to allow the turning of the key 71 from the desired position in the key board. The slight vertical movement of the push rod 61 caused by the slight vertical movement of crank pin 60 will be permitted by elongating slot 64 vertically.

In the operation of a typewriter constructed in accordance with this invention, the operator may swing the rack bar 30 rearwardly and upwardly so as to be more accessible, and the clip 34 is then adjusted along the rack bar 30 to a position where the end of the margin or line is to be determined or stopped. The bar is then released and falls into the position shown in full lines in Fig. 1. In shifting the clip along the rack bar, it is merely necessary to depress the latch piece 37 against the action of the spring 50, sufficiently to disengage the flanges 40 from the notches 41, which releases the clip for sliding movement. When the clip has been repositioned, the flanges 40 will return into the notches 41 as soon as the latch piece 37 is released, owing to the action of the spring 50 which normally urges the latch piece upwardly.

During the operation of the printing mechanism, as in typing a line, the type bars carried by the segment will operate the universal bar 9, and the link 17 connected to the latter will be given a motion of endwise translation. The lever 25 is normally in the angular position shown in Fig. 1, and holds the locking pawl 22 out of the path of the link 17. The other end 29 of the lever 25 is in the full line position shown in Fig. 1 and within the path of the cam lever 52 of the clip as it travels with the carriage through increments of motion permitted by the escapement mechanism which is also operated at each operation of the type-bars.

When the desired end of the line has been

reached, as determined by the position of the clip 34 upon the rack bar 30, the end 51 of the cam lever 42 will engage with the free projecting arm 29 of the lever 25 and 5 depress it into the dash line position shown in Fig. 1. When the arm 29 is depressed, the other arm 27 of the same lever will be elevated, and will shift the locking pawl 22 into the path of the link 17 so as to prevent 10 translation thereof. This locks the universal bar against movement, and the latter prevents movement of the type bars of the printing mechanism into printing positions. This serves as an indication to the operator 15 that the end of the line has been reached, which determines the right margin of the matter being typed upon a page.

Preferably a bell or similar signal device is operated by the pin 53 just prior to the 20 locking of the printing mechanism, which serves as an audible advance signal to the operator that the end of the line has been about reached.

It frequently happens that when the line 25 lock thus described has become effective, a syllable or word is incomplete and could be completed by the printing of one or more letters. To permit this, the operator pushes the key 71 rearwardly and this shifts the rod 30 61 rearwardly, thus rocking the crank arm 56 against the rack bar 30 and rocking the latter rearwardly sufficiently to carry the cam lever 42 off the end of the lever arm 29. Immediately that this happens, the lever 35 arm 29 will move upwardly into its normal position and the locking pawl 22 will descend into its inactive position, releasing the printing mechanism.

When the key 71 is released, the spring 40 57 will retract the arm 56 from the rack bar 30 and permit the latter to swing into its normal position shown in Fig. 1. In so swinging the face of the cam lever 42 will strike against the end of the lever arm 29 45 so that the carriage may continue its travel without again depressing the lever arm 29 and locking the printing mechanism. In this manner, a limited amount of further typing may be accomplished.

50 The cam lever, during its movement with the carriage in either direction after release from the lever 29, will ride against the end of the same until it clears it, and then the rack bar will return entirely to the normal 55 position shown in full lines in Fig. 1. If the lever 42 is moved entirely beyond the arm 29 in a further printing operation, and the carriage is then returned, the end portion 52 of the lever 42 will engage the lever 29 60 and cam it downwardly against the action of the spring 25 and temporarily lock the printing mechanism, although no harm comes therefrom since one would not be likely to operate the printing mechanism 65 while the carriage is traveling toward its

initial or starting position. The slot 47 limits the movement of the lever 42 so that it will normally be held in proper position to engage and depress the lever arm 29 at the end of a line.

70 It will be observed that with this construction, one may readily determine the end of a line or margin by properly positioning the clip 34 upon the rack bar 30. The printing mechanism will be automatically locked 75 when the carriage reaches a selected point in its travel and this locking mechanism may be released to permit of a limited further operation of the printing mechanism by merely pressing upon the key 71. Such 80 mechanism is relatively simple and formed largely of stock material, such as sheet metal, wire rods, springs, etc., and may be arranged in the usual typewriter without necessitating material rearrangements or 85 changes in the other typewriter mechanism.

It will be observed that with this improved construction the locking of the printing mechanism by the margin stop does not interfere with the travel of the carriage. It is only the type bars and the key lever system which are locked against further movement and the carriage may be operated further in letter feeding direction by the space bar or by releasing the carriage 95 through the usual carriage release mechanism, not shown.

100 It will be obvious that various changes in the details, which have been herein described and illustrated for the purpose of explaining the nature of the invention, may be made by those skilled in the art within the principle and scope of the invention as expressed in the appended claims.

105 I claim:—

1. In a typewriting machine, a frame, a carriage movable across the frame, printing mechanism, a universal bar operable by the printing mechanism, a link connected at one end to said universal bar, a support for 110 slidably mounting the other end of said link, a stop movable into and out of the path of said link, and means controlled by the carriage for shifting said stop into the path of said link to prevent operation of the universal bar and thereby of the printing mechanism when the carriage has reached a predetermined point in its travel.

115 2. In a typewriting machine, a frame, a carriage movable across the frame, printing mechanism, a universal bar operable by the printing mechanism, a link connected at one end to said universal bar, a support for 120 slidably mounting the other end of said link, a stop movable into and out of the path of said link, means controlled by the carriage for shifting said stop into the path of said link to prevent operation of the universal bar and thereby of the printing mechanism when the carriage has reached a 125 130

predetermined point in its travel, and means for interrupting the control of said stop by said carriage whereby further operation of the printing mechanism and further travel 5 of the carriage may be obtained.

3. In a typewriting machine, a frame, a carriage movable across the frame, a stop bar hinged to said carriage for normal movement therewith and capable of swinging laterally of the direction of travel of the carriage, a margin stop carried by said bar, printing mechanism, means operated by said margin stop to obstruct operation of the printing mechanism at a selected point in 15 the travel of the carriage while permitting the carriage to travel and mechanism for swing the stop bar laterally of the travel of the carriage to disengage it from said means to permit further operation of the printing 20 mechanism.

4. In a typewriting machine, a frame, a carriage movable across the frame, a stop bar carried by the carriage for travel therewith, and hingedly connected thereto so as 25 to swing laterally of the direction of the travel of the carriage, printing mechanism, a margin stop carried by said bar, means carried by said frame and adapted when operated to prevent operation of said printing 30 mechanism but permit continued movement of the carriage, said means including an operating member in the normal path of travel of said stop, so as to be operated thereby to check operation of the printing mechanism when the carriage has reached a selected point in its travel, and means carried by said frame and operable laterally 35 against said bar to swing it out of the path of said member to release the printing mechanism.

5. In a typewriting machine, a frame, a carriage movable across the frame, a stop bar carried by the carriage for travel therewith and hingedly connected thereto so as to swing 45 laterally of the direction of the travel of the carriage, printing mechanism, a margin stop carried by said bar, means carried by said frame and adapted when operated to prevent operation of said printing mechanism, said 50 means including an operating member in the normal path of travel of said stop, so as to be operated thereby to check operation of the printing mechanism when the carriage has reached a selected point in its travel, an arm pivoted to said frame and shiftable transversely of said bar at any point in the travel of the carriage to engage and swing it out of engagement with the operating member of said means, to effect a release of 55 the printing mechanism, and means for rocking said arm to effect a release of said printing mechanism.

6. In a typewriting machine, a segment, printing mechanism carried by said segment, a universal bar carried by said segment, a

link pivoted at one end to said universal bar, means supporting the other end of said link so that operation of said universal bar will cause translation of said link in an endwise direction, a pivoted pawl movable 70 across the path of travel of said link to prevent such translation, and means controlled by the carriage for shifting said pawl into a position to prevent operation of said link when the carriage has reached a selected 75 point in its travel.

7. In a typewriting machine, a segment, printing mechanism carried by said segment, a universal bar carried by said segment, a link pivoted at one end to said universal bar, means supporting the other end of said link so that operation of said universal bar will cause translation of said link in an endwise direction, a pivoted pawl movable 80 across the path of travel of said link to prevent such translation, a lever pivoted to said frame and operable upon said stop pawl to shift it into the path of travel of said link, and means carried by the carriage for operating said lever automatically when the carriage reaches a selected point in its travel, whereby at such selected point further operation of the printing mechanism will be prevented.

8. In a typewriting machine, a segment, printing mechanism carried by said segment, a universal bar carried by said segment, a link pivoted at one end of said universal bar, means supporting the other end of said link so that operation of said universal bar will cause translation of the link in an endwise direction, a pivoted pawl movable 95 across the path of travel of said link to prevent such translation, a lever pivoted to said frame and operable upon said stop pawl to shift it into the path of travel of said link, means carried by the carriage for operating said lever automatically when the carriage reaches a selected point in its travel, whereby at such selected point further operation of the printing mechanism will be prevented, and mechanism for disengaging said means from said lever.

9. In a typewriting machine, a frame, a carriage movable across the frame, a stop device carried by said carriage for travel therewith and movable thereon laterally of the direction of travel of said carriage, printing mechanism, means movable into a position to obstruct operation of said printing mechanism, said means having an operating member in the path of travel of said stop device for displacement by the stop device as the latter passes, whereby during the interval while the stop device is passing a selected point in its travel with the carriage, said means will cause an obstruction to the operation of the printing mechanism without interference with the travel of the carriage, and mechanism for shifting said stop 115

120

125

130

device laterally of the direction of travel of the carriage to release said operating member and permit further operation of the printing mechanism.

5 10. In a typewriting machine, a frame, a carriage movable across the frame, a bail-shaped bar hinged to said carriage so as to swing in a direction forwardly and rearwardly, printing mechanism, means for obstructing operation of said printing mechanism including an operating member adjacent said bar, an element carried by said bar and operating on said member to set it to obstruct operation of said printing mechanism during the interval in which said element is passing a selected point in its travel with the carriage, and means for engaging and swinging said bar out of engagement with said operating member to release the printing mechanism for further operation.

15 11. In a typewriting machine, a frame, a carriage movable across the frame, a stop bar carried by said carriage and hinged thereto for movement laterally of the direction of travel of said carriage, a margin stop element carried by said bar, a lever having an operating end terminating in proximity to and in the path of travel of said margin stop element to be rocked thereby, whereby 20 while the stop element is passing a selected point in its travel with the carriage, it will engage and depress and hold depressed the end of said lever, printing mechanism, means operable by said lever when depressed for obstructing operation of said printing mechanism without interference with the travel of the carriage, and a device for swinging said bar laterally of its travel with the carriage to disengage it from said lever and release the printing mechanism for further operation.

25 12. In a typewriting machine, a frame, a carriage movable across the frame, a stop bar carried by said carriage and movable thereon laterally of the direction of travel of said carriage, a stop element carried by said bar, said element having a cam flange extending in a plane parallel to the direction of travel of said bar, a lever having an operating end 30 extending in a direction transversely of the travel of the carriage and terminating in proximity to and in the path of said flange, whereby when the stop element on said carriage passes a selected point in its travel the flange will engage said end of the lever and rocked, printing mechanism, means operable by said lever when so rocked for obstructing operation of said printing mechanism, and a device for shifting said bar laterally to disengage it from the end of the lever and thereby release the printing mechanism for further operation, said bar when released moving toward normal position until said flange lies across the end of the 35 lever and being held in that position until

the carriage has traveled further to an extent sufficient to release the flange from the lever.

13. In a typewriting machine, a frame, a carriage moving across the frame, printing mechanism, means for obstructing operation of said printing mechanism including a lever having a free operating end in proximity to the carriage, and cam means provided on said carriage to engage and rock said lever and hold it in a position to obstruct operation of the printing mechanism while the carriage is passing a selected point in its travel.

14. In a typewriting machine, a frame, a carriage moving across the frame, printing mechanism, means for obstructing operation of said printing mechanism including a lever having a free operating end in proximity to the carriage and extending in a direction transversely to its direction of travel, cam means provided on said carriage to engage and rock said lever when the carriage reaches a selected point in its travel, said cam means being movable laterally of its travel away from the end of said lever and laterally against the end portion of said lever, and a device for shifting said cam means laterally of its travel to release said lever and thereby release said printing mechanism, said cam means when released being held in released position by its engagement with the end portion of the lever until the carriage travels to an extent sufficient to carry the cam means entirely out of engagement with the lever.

15. In a typewriting machine, a frame, a carriage movable across the frame, printing mechanism, means for obstructing the operation of said printing mechanism including a lever having an operating arm extending into proximity to said carriage and extending in a direction transversely of the direction of travel of said carriage, cam means supported by said carriage and movable therewith and disposed to engage and operate said lever arm at a selected point in the travel of the carriage, said cam means being movable laterally of its path of travel out of engagement with the lever, a crank member having an arm engageable with said cam means to shift it out of engagement with said lever, a spring normally holding said crank member in inactive position, and a key device connected to said crank member for operating the same to effect a shifting of the cam means and thereby effect a release of the lever.

16. In a typewriting machine, a frame, a carriage movable across the frame, a stop bar extending parallel to and carried by said carriage and supported for movement laterally of the direction of travel of the carriage, printing mechanism, means movable into a position to obstruct operation of said printing mechanism and including a lever having an operating end in proximity to said stop

- bar, the stop bar having a cam portion engaging with and operating said lever when the carriage reaches a selected point in its travel, a rod extending in a direction lengthwise of the travel of the carriage and having two crank arms thereon, one of said crank arms movable into engagement with said stop bar to shift it laterally out of engagement with said lever and thereby release said printing mechanism for further operation, a push rod connected to the other crank arm for rocking said rod, means normally holding said rod in a position with its top bar operating arm in inactive position, and a key device connected to said push rod to operate the same.
17. In a typewriting machine, a frame, a carriage operable across the frame, printing mechanism, means for obstructing operation of said printing mechanism automatically when the carriage reaches a selected point in its travel, a push rod slidingly supported by said frame, a key device connected to one end portion of said rod for operating the same in an endwise direction, the end of said rod being bent laterally and then backwardly to form a loop, a crank device having an arm engaging in said loop so as to be rocked thereby when the rod is shifted endwise, said crank device having a member operable to release said printing mechanism when shifted by said key, and means for normally retracting said crank device into inactive position.
18. In a typewriting machine, a frame, a carriage movable across the frame, a segment, printing mechanism carried by said segment, a universal bar carried by said segment in a position to be operated by said printing mechanism, a link connected at one end to said universal bar for movement therewith, said link being also supported by said frame for movement in a substantially endwise direction when operated by said universal bar, a stop element mounted on said frame and movable into a position to prevent operation of said link by said universal bar, a lever mounted on said frame and connected to said element to operate the same when the lever is rocked, and means provided on the carriage for rocking said lever in a direction to shift said element into a position where it locks movement of said universal bar whenever the carriage reaches a selected point in its travel.
19. In a typewriting machine, a frame, a carriage movable across the frame, a segment, printing mechanism carried by said segment, a universal bar carried by said segment in a position to be operated by said printing mechanism, a link connected at one end to said universal bar for movement therewith, said link being also supported by said frame for movement in a substantially endwise direction when operated by said universal bar, a stop member mounted on said frame and movable against the end of said link to prevent its operation by said universal bar, a lever mounted by said frame and connected at one end to said member to operate the same when the lever is rocked, and means provided on the carriage for rocking said lever in a direction to shift the member into a position where it locks movement of said universal bar whenever the carriage reaches a selected point in its travel, and means for disengaging the lever operating means from the lever to release the universal bar.
20. In a typewriting machine, a frame, a carriage movable across the frame, a stop bar carried by the carriage and having rack teeth therealong, a clip embracing and slideable along said bar, a cam lever pivoted at one end to said clip and extending parallel with said bar, said clip having a vertically extending slot therein, said lever having a tongue extending therefrom in said slot to limit the oscillatory movement of said lever.
21. In a typewriting machine, a frame, a carriage movable across the frame, a stop bar carried by the carriage and having rack teeth therealong, a clip embracing and slideable along said bar, a cam lever pivoted at one end to said clip and extending parallel with said bar, said clip having a vertically extending slot therein, said lever having a tongue extending therefrom into said slot to limit the oscillatory movement of said lever, and a spring device carried by said clip and engaging with said lever to yieldingly hold it at one limit of its oscillatory movement.
22. In a typewriting machine, a frame, a carriage movable across the frame, a stop bar carried by the carriage and having rack teeth therealong, a clip embracing and slideable along said bar, a cam lever pivoted at one end to said clip and extending parallel with said bar, said clip having a vertically extending slot therein, said lever having a tongue extending therefrom into said slot to limit the oscillatory movement of said lever, a latch element carried by said clip for movement in a direction edgewise of said bar, said latch extending along one face of the bar and having a tongue extending therefrom along the edge of the rack teeth, whereby when the latch element is shifted in said clip, the tongue will move into and out of engagement with the rack teeth to lock the clip against sliding movement along the bar, and a spring for yieldingly urging the latch device in a direction to engage said tongue with said rack teeth.
23. In a typewriting machine, a frame, a carriage movable across the frame, a stop bar carried by the carriage and having back teeth therealong, a clip embracing and slideable along said bar, a cam lever pivoted at one end to said clip and extending parallel with said bar, a lever mounted by said frame and connected at one end to said member to operate the same when the lever is rocked, and means provided on the carriage for rocking said lever in a direction to shift the member into a position where it locks movement of said universal bar whenever the carriage reaches a selected point in its travel, and means for disengaging the lever operating means from the lever to release the universal bar.

- with said bar, said clip having a vertically extending slot therein, said lever having a tongue extending therefrom into said slot to limit the oscillatory movement of said lever, 5 5 a latch element carried by said clip for movement in a direction edgewise of said bar, said latch extending along one face of the bar and having a tongue extending therefrom along the edge of the rack teeth, where- 10 10 by when the latch element is shifted in said clip, the tongue will move into and out of engagement with the rack teeth to lock the clip against sliding movement along the bar, and a spring interposed between the latch 15 15 device and the lever for yieldingly urging said latch device in a direction to engage its tongue with the rack teeth and urge said lever into one of its limited positions.
24. In a typewriting machine, a carriage, 20 20 a rack bar supported by said carriage for movement therewith, a clip fitting against one face of the bar and having its edges turned over and slidingly engaging both edges of said bar, whereby the clip may 25 25 slide along said bar and be confined thereon, said clip having apertures in its upper and lower edges, a latch piece passing through said apertures and across one face of the bar from edge to edge, said latch piece hav- 30 30 ing at one end a tongue engaging with the teeth of said rack bar and movable out of engagement with said teeth when the latch piece is moved endwise, and a spring acting upon said latch piece to normally shift it in a 35 35 direction to engage its tongue with the rack teeth.
25. In a typewriting machine, a carriage, a rack bar supported by said carriage for movement therewith, a clip fitting against 40 40 one face of the bar and having its edges turned over and slidingly engaging both edges of said bar, whereby the clip may be confined upon and slide along said bar, said clip having apertures in its upper and lower 45 45 edges, a latch piece passing through said apertures and across one face of the bar from edge to edge, said latch piece having at one end a tongue engaging with the teeth of said rack bar and movable out of engage- 50 50 ment with said teeth, when the latch piece is moved endwise of itself, the end of said latch piece opposite from the tongue extending over the latch bar and down the other face of the bar, a lever hinged at one end to 55 55 said clip, said lever and clip having inter- engaging portions limiting the oscillatory movement of the lever thereon, said lever having a flange provided with an aperture, the last named portion of the latch piece 60 60 being reduced in lateral dimensions and ex- tending through the aperture in the flange of said lever, and a spring surrounding the re- duced portion of the latch piece, abutting at one end against said flange of the lever, and 65 65 at its other end against the larger portion

of said latch piece, so as to normally urge the latch piece in a direction to engage its tongue with the rack teeth of the bar and also urge said lever in one direction.

26. In a typewriting machine, a segment, 70 printing mechanism carried by said segment, a universal bar operated by the printing mechanism, a link pivoted at one end to said universal bar, means supporting the other end of said link so that operation of said universal bar will cause translation of said link in an endwise direction, a pivoted pawl movable across the path of travel of said link to prevent such translation, and means controlled by the carriage for shifting said 75 pawl into a position to prevent operation of said link when the carriage has reached a selected point in its travel.

27. In a typewriting machine, a segment, 80 printing mechanism carried by said segment, a universal bar operated by the printing mechanism, a link pivoted at one end to said universal bar, means supporting the other end of said link so that operation of said universal bar will cause translation of said link in an endwise direction, a pivoted pawl movable across the path of travel of said link to prevent such translation, a lever pivoted to said frame and operable upon said stop pawl to shift it into the path of travel of said link, and means carried by the carriage for operating said lever automatically when the carriage reaches a selected point in its travel, whereby at such selected point further operation of the printing mechanism will be prevented. 90

28. In a typewriting machine, a segment, 95 printing mechanism carried by said segment, a universal bar operated by the printing mechanism, a link pivoted at one end to said universal bar, means supporting the other end of said link so that operation of said universal bar will cause translation of the link in an endwise direction, a pivoted pawl movable across the path of travel of said link to prevent such translation, a lever pivoted to said frame and operable upon said stop pawl to shift it into the path of travel of said link, means carried by the carriage for operating said lever automatically when the carriage reaches a selected point in its travel, 105 whereby at such selected point further operation of the printing mechanism will be prevented, and mechanism for disengaging said means from said lever. 110

29. In a typewriting machine, a carriage, 115 printing mechanism, a stop element movable with said carriage, and means including a member in the path of and operable by said stop element, as the latter is passing a selected point in its travel with the carriage, for obstructing operation of the printing mechanism without interference with the travel of the carriage, said stop element being 125 at will independently movable on the car- 130

riage to release said member and permit continued operation of the printing mechanism.

30. In a typewriting machine, a carriage, a plurality of printing devices, means including a control member mounted for approximately rectilinear movement and operable by any one of said devices, a stop device including a member movable into and out of a position in which it obstructs rectilinear movement of said control member, a stop element movable with said carriage, and

operable automatically upon said stop device to cause movement of said obstructing member into obstructing position while the stop element is moving with said carriage 15 past a selected point in its travel, said stop element being movable at will out of control of said stop device to release the printing devices for further operation.

In witness whereof, I hereunto subscribe 20 my signature.

JOHN H. BARR.
